PAINT SPRAY BOOTH

Rubert M. Richards, Detroit, Mich., assignor to
 Industrial Sheet Metal Works, Inc., Detroit,
 Mich., a corporation of Michigan

Application April 25, 1939, Serial No. 269,967

3 Claims. (Cl. 91—60)

This invention relates to improvements in wet booth structures such as are exemplified in spray booths wherein articles or structures are paint sprayed.

5 An object is to provide an improved booth structure of the character described wherein the air stream that is withdrawn therethrough is filtered and cleaned of foreign material picked up by the stream by the improved structure here disclosed. Specifically the improvement relates to the provision of means in the form of a curtain or the like, which curtain is advanced across the path of the air stream flowing through the booth to intercept the movement of the foreign 10 material particles carried by the air stream removing such particles therefrom, and depositing the same. The reclaimable portion of such foreign particles such as the paint particles may be salvaged and the undesired foreign material particles may be wasted. Means is provided to continuously clean the curtain during its advance of any foreign particles collected on the curtain.

The improved curtain is so constructed that the air stream can pass readily therethrough but foreign material particles of a liquid or solid state carried by the air cannot pass directly therethrough but are intercepted by the curtain and either knocked down by it into a collector basin or receptacle or picked up by the curtain and 20 washed therefrom by the washing means which is provided for this purpose.

An important characteristic is that the curtain presents a multiplicity of porous thicknesses to the passage of the air stream therethrough and that the curtain is revolvable continuously across such air stream. At its lower end the curtain is presented to a liquid washer which continuously cleans it. Furthermore, the curtain being wet as it leaves the washer presents a wet surface to the passage of the air stream therethrough which serves more effectively to intercept the passage of foreign particles carried by the air.

More particularly, the filter curtain is made up of a succession of screen mesh strips which are arranged in shingled overlapping relationship. The individual strips are pivotally supported for swingable movement at provided times during the revolution of the curtain. As the curtain is advanced across the air stream these porous overlapping strips are held in contacting overlapping relationship by means which is provided for the purpose. As the curtain moves through the vat of cleaning fluid the strips are 50 preferably allowed to swing and separate from

each other to facilitate the cleaning of the strips. Preferably also, separate fluid cleaning means is associated with the curtain and may be arranged at one end between the front and rear curtain wall sections. 5

Other objects, advantages and meritorious features of this invention will more fully appear from the following description, appended claims, and accompanying drawings, wherein:

Figure 1 is an end elevation partly broken away 10 and taken on the line of 1—1 of Fig. 2.

Fig. 2 is a rear elevation taken at right angles to the view in Fig. 1 and being also partly in section and broken away to show the construction, 15

Fig. 3 is a horizontal sectional view taken on 15 line 3—3 of Fig. 2.

Fig. 4 is a vertical sectional view through a fragment of the curtain structure, and

Fig. 5 is an elevation of a fragment of the curtain structure to show the pivotal support of 20 the overlapping screen section.

This invention is shown as embodied in a paint spray booth which is widely used in the manufacturing industry for the painting of both large and small articles and wherein paint is sprayed 25 by an operator upon the articles as they are hung within the booth or advanced therethrough. It is of the type commonly known as a wet booth.

This invention relates to the cleaning of the air stream as it is exhausted from the booth and 30 to the removal of foreign material particles from such air stream to prevent them passing out with the exhausted air and also to reclaim such particles as are capable of salvage for re-use such as the paint particles. Such booth comprises an 35 enclosure within which the articles can be sprayed or hung and through which the air stream is withdrawn and an exhaust air duct adapted to draw a stream or current of air through the booth and means for removing the solid or liquid 40 particles carried by the air from the air stream and knocking them down into a receptacle from which they may later be removed.

In the drawings herewith the enclosure is indicated generally as 10 and comprises side walls, 45 a bottom and top wall and is open at the front. At the rear the enclosure is provided with an enlargement which is also a walled in extension of the enclosure and indicated as 12 in Fig. 1. This enlargement is continuous and open at the bottom into a liquid carrying vat indicated generally as 14 in Fig. 1. This vat has a lid or cover 46 through which its contents may be removed and inspected. The rear wall of the rear enlarged portion of the enclosure is cut through with an 50

55

air exhaust duct 18 through which a stream of air is drawn so as to maintain a current of air flowing actively through the enclosure at all times. This carries away the paint fumes and vapor particles in the air and provides clean fresh air always flowing through the enclosure. This assemblage of elements is conventional in paint spray booths of the present time.

I provide a revolvably supported foraminous curtain indicated generally as 20 in Fig. 1 which is adapted to be advanced across the air stream travelling through the booth for discharge through the exhaust duct 18. This curtain may be supported at opposite ends for advancement upon upper and lower shafts 22 and 24, respectively. These shafts are here shown as provided with gear elements 26 and 28 respectively. The shafts may be driven in any suitable manner. An electric motor 30 is here shown which drives 20 through a chain drive and gear mechanism indicated generally as 32. The upper shaft 22 drives the curtain 20 through sprocket gears 26.

The curtain comprises longitudinal side chains 34 made up of suitably connected links which mesh with the upper sprocket gears 26 and the lower sprocket gears 28 so that the curtain is driven upon rotation of the shaft 22 as described. These links are fitted with supporting means here shown as lugs 36 which carry tubular elements 38 into which are fitted the cylindrical ends of bars 40. Fig. 4 is through an intermediate section of the bars at which point they are shown as square. Obviously they might be of any desired shape. The cylindrical ends are fitted within the elements 38 so that the bars and the screen mesh strips carried thereby have a permitted swinging movement as hereinafter described.

The curtain is made up of a succession of 40 foraminated curtain elements here shown as screen mesh strips. A strip of screen 42 is secured to each curtain element and extends down overlapping screen mesh strips therebelow. The overlapping element may be as desired, but as here shown some four overlapping thicknesses are illustrated. The lower edge of each screen strip may be provided with an edge binding 44 which serves to hold the screen mesh in alignment and cause it to hang flat.

50 It will be seen that guide rails indicated as 46 are illustrated in Fig. 1 and that the guide rails are so disposed with respect to the extent of the front and rear elevations of the curtain as to hold the overlapping screen strips in contact 55 tacting overlapping relationship as they are advanced across the air stream. The guide rails terminate at about the upper level of the vat or tank 14 so that as the strips enter the tank they are permitted to fall apart so that when 60 they are passed through the cleaning liquid they will be more effectively cleaned. The tank contains any suitable type of cleaning liquid, carbon tetrachloride, or any other suitable paint dissolving or removing solvent and the level might 65 be as indicated in the view of Fig. 1.

This cleaning fluid is preferably recirculated and a conventional recirculating pump 50 driven by a motor 52 (Figs. 2 and 3) may be employed. The communication pipe 54 from the pump leads 70 to a spray pipe or tube 56 within the vat which is provided with discharge nozzles to spray cleaning liquid toward both the front and rear surfaces of the curtain and a separate spray tube 58 may be led off to spray liquid against the 75 opposite surfaces of the screen strips. This

pump communicates with the vat so that a continuous circulation is maintained.

It will be seen that in the operation of the structure the articles to be sprayed which are positioned within the enclosure 10 are sprayed 5 with paint which will strike against the curtain as it is advanced across the rear of the enclosure and any solid or liquid particles of the paint spray fluid or other foreign matter which is picked up by the air stream being drawn through 10 the enclosure will be intercepted by the revolving curtain which is preferably continuously being advanced and will be either knocked down into the vat 14 or picked up by the curtain and carried along thereby upon the screen mesh strips 15 to be washed from such strips as they move through the vat.

The overlapping of the plurality of thicknesses of screen mesh will provide air passageways through the curtain for the passage of air stream 20 but these passageways due to the overlapping arrangement of the successive strips of mesh will be of such a tortuous character that there will not be any direct passageway for solid or liquid particles of material to pass with the air stream 25 therethrough. Due to the fact that the air stream is continuously wet by the cleaning fluid it will have an even greater tendency to pick up any particles that are not knocked down by it into the vat and these will be washed therefrom 30 as the successive strips swing through the cleaning fluid of the vat and are exposed to the liquid vat streams discharged from the spray pipes 56 and 58 so that the surface of the curtain that is presented to the paint spray in the enclosure 35 will be kept clean and the strips will not become fouled with material so as to require constant cleaning but will remain relatively free of foul material.

What I claim is:

40 1. A wet booth of the character described having side walls forming an enclosure, an air exhaust duct communicating with the interior of the booth to withdraw an air stream therefrom, an endless belt air filter curtain supported for advancement across the air stream passing through the booth into the air duct, said curtain comprising a succession of screen mesh strips arranged in shingled overlapping relationship presenting at all points of the curtain advancing 50 across the air stream a plurality of overlapped screen strips, said strips being individually pivotally supported for permitted swingable movement and through which the air stream must pass for exhaust from the booth, and a source 55 of liquid supply adapted to wet said screen strips during their advance.

2. A wet booth of the character described having side walls forming an enclosure, an air exhaust duct communicating with the interior of 60 the booth to withdraw an air stream therefrom, an endless belt air filter curtain supported for advancement across the air stream passing through the booth into the air duct, said curtain being formed of a succession of screen mesh strips supported for endless belt advancement and arranged in shingled overlapping relationship presenting at all points in the rise of the curtain a plurality of screen mesh thicknesses and through which the air stream must pass for 70 exhaust from the booth, said strips being individually pivotally supported for swingable movement during the advance of the curtain, means holding said strips in contacting overlapping relationship throughout the length of 75

rise and fall of the curtain across the air stream, and a liquid vat through which the lower end of the curtain travels.

3. A wet booth of the character described having side walls forming an enclosure, an air exhaust duct communicating through one of said walls with the interior of the booth to withdraw an air stream therefrom, an endless belt curtain structure comprising a succession of screen mesh strips disposed in shingled overlapping relationship presenting at all points in the rise of the curtain a plurality of screen mesh thick-

nesses and supported to be advanced across the path of the air stream passing from the booth into said duct, said screen strips being individually pivotally supported for swingable movement, means holding said strips in contacting overlapping relationship during the advance of the curtain across said air stream, and a liquid containing vat through which the bottom of the curtain is advanced, spray means disposed within the endless belt curtain to spray liquid cleaner upon the inner surface of the curtain.

RUBERT M. RICHARDS.
